ELASTIC FABRIC AND COLORED STRAND
THEREFOR

Frederick P. Jecusco, Middletown, Conn., as-
signor to The Chatham Manufacturing Com-
pany, Portland, Conn., a corporation

Application December 3, 1934, Serial No. 755,662

9 Claims. (Cl. 28—1)

This invention relates to elastic strands and particularly to colored elastic strands for incorporation into woven, knitted or netted elastic fabrics, etc., as well as to such fabrics themselves. 5 The present application constitutes a continuation in part of my co-pending application, Serial No. 709,408, filed February 2, 1934.

One of the objects of the present invention is to provide a superior elastic strand highly pleasing to the aesthetic sense.

10 A further object is to provide a unitary elastic strand capable of producing novel and attractive multitone effects when incorporated into elastic fabrics.

15 Another object of the present invention is to provide an attractive and colorful elastic fabric.

A still further object is to provide a novel elastic fabric having changeable color effects as the tension on the fabric is changed.

20 Other objects and advantages will appear to those skilled in the art from the following, considered in conjunction with the accompanying drawing and appended claims.

In the accompanying drawing:

25 Fig. 1 is a broken perspective view of an elastic strand embodying the present invention;

Fig. 2 is a schematic representation of an elastic fabric having incorporated therein multitone elastic strands, the fabric being represented as in 30 its contracted condition; and

35 Fig. 3 is a corresponding view indicating the elastic fabric as having been materially stretched to thus produce a changed multitone effect.

The particular elastic strand 10 herein chosen 40 for illustration is composed of a plurality of irregularly-shaped bodies of differentially-colored elastic material such, for instance, as rubber, latex or other suitable elastic material. The said plurality of bodies may vary in size and shape and may, for instance, comprise red bodies 11, blue bodies 12, yellow bodies 13, black bodies 14 and white bodies 15, as indicated in the drawing. These differentially-colored bodies may be organized into a unitary strand in any approved manner. In addition to being of irregular shape, the 45 differentially-colored bodies 11, 12, 13, 14 and 15 are irregularly disposed in the strand 10 along all three dimensions thereof.

In producing the elastic strand above described, 50 a plurality of masses of plastic rubber, respectively having the desired individual coloration, may be kneaded together and rolled into a sheet which may be later vulcanized and subsequently cut into strands such as 10. Other methods of manufacture will readily suggest themselves to

those skilled in the art, such, for instance, as an extrusion process.

The terms "color" and "coloration" as used herein are to be understood, for the purpose of convenience of description, as including black and 5 white as well as combinations of the same and other tints or colors.

As above pointed out, the various masses of differentially-colored rubber are molded or otherwise suitably organized together so that, while 10 they are visually distinct one from the other, owing to their distinctive coloration, they nevertheless form a physically-unitary strand. It will be noted that the various bodies of the strand 10 15 preferably each have length, width and depth, rather than mere surface coloration, so as to be properly characterized as of "three dimensional" extent.

In Figs. 2 and 3 of the drawing are schematically shown a fabric comprising interwoven warp 20 strands 16 and weft strands 17 formed of cotton, rayon, silk, or other so-called "textile material," and also having interwoven therewith a plurality of elastic strands 10 like that shown in Fig. 1. If desired, ordinary rubber strands or multicolored 25 strands like 10 may be included in the weft.

In Figs. 2 and 3 just referred to, no effort has been made to indicate more than a surface ply of the fabric, inasmuch as the number of plies 30 and the character of the weave may vary widely 35 within the scope of the present invention, and the inclusion in the background of additional plies, together with their binding strands, etc., would cause confusion and, therefore, serve no useful purpose. While the multitone elastic strands 10 are shown as lying straight in the fabric, it will be appreciated that in the weaving of fabrics, some or all of these strands will almost inevitably become twisted, but this fact, rather than being 40 harmful, would add to the attractiveness of the 45 multitone effect herein referred to.

Inasmuch as the various differentially-colored bodies 11 to 15 inclusive in effect transversely divide or partly divide a given face of the strands 45 10 into varied color zones or spots, when the tension on the fabric is changed, as, for instance, when the fabric is stretched from the condition shown in Fig. 2 to that shown in Fig. 3, these various multicolor spots change in dimensions 50 and are elongated. For instance, given bodies or spots such as 15a, while having their greatest dimensions extending in directions other than longitudinally of the fabric when the elastic strands are relaxed as in Fig. 2, alter materially 55

in shape, as will be seen by comparing the said bodies 15^a in Fig. 2 with the same bodies as they appear in Fig. 3 when the strands are under greater tension. It will be appreciated, of course, that as the elastic strands 10 are stretched longitudinally, they will, at the same time, contract their transverse dimensions.

The novel elastic strands 10, when woven or otherwise incorporated into a fabric, produce an extremely attractive variegated effect therein, owing largely to the three-dimensional disposition of their visually-distinct but physically-unitary differentially-colored bodies 11, 12, 13, 14 and 15. As a matter of fact, when the tension on the fabric changes, the various colored bodies seem to scintillate through the relatively-inelastic warp and weft strands 16 and 17 as the fabric is stretched and released, the effect being quite remarkable, inasmuch as the color-patterns show differently through the interstices of the fabric for substantially each different tension under which the fabric may be placed. An added effect is also obtained if the threads extending crosswise of the multicolored elastic strands are of semi-transparent material such as rayon or silk.

The elastic strands 10 above described are of conventional rectangular cross-sectional form, but it will be obvious without further illustration that they may be of other than the cross-sectional form shown, such, for instance, as the common round form. Furthermore, the number and coloration of the various differentially-colored portions may be varied as desired.

The invention may be carried out in other specific ways than that herein set forth without departing from the spirit and essential characteristics of the invention, and the present embodiment is therefore to be considered in all respects as illustrative and not restrictive, and all changes coming within the meaning and equivalency range of the appended claims are intended to be embraced therein.

I claim:

1. An elastic fabric having included therein one or more elastic strands each having variegated surface-areas or zones of differential coloration, size and shape dispersed thereon substantially throughout its length and changeable in shape in response to changes in the tension to which the fabric is subjected.

2. An elastic fabric having included therein one or more elastic strands each having variegated surface-areas or zones of differential coloration, size and shape irregularly disposed thereon and

changeable in shape in response to changes in the tension to which the fabric is subjected.

3. An elastic fabric having included therein one or more elastic strands each having irregularly-disposed and irregularly-shaped differentially-colored areas or zones dispersed thereon and changeable in shape in response to changes in the tension to which the fabric is subjected.

4. An elastic fabric having included therein a plurality of elastic strands, each of which is composed of a plurality of three-dimensional bodies of elastic material of differential coloration and shape, the said differentially-colored bodies being changeable in shape in response to changes in the tension to which the fabric is subjected.

5. An elastic fabric including one or more elastic strands and a plurality of cross-strands extending crosswise of the said elastic strands, the said elastic strands each having variegated surface-areas or zones of differential coloration, size and shape dispersed thereon and showing through the interstices between the said cross-strands in changing patterns as the tension applied to the fabric is changed.

6. A unitary elastic strand of a cross-sectional size suitable for incorporation in fabrics and having variegated surface-areas or zones of differential coloration changeable in shape in response to changes in the tension to which the strand is subjected.

7. A unitary elastic strand of a cross-sectional size suitable for incorporation in fabrics and having variegated surface-areas or zones of differential coloration irregularly disposed thereon and dispersed substantially throughout the length of the strand and changeable in shape in response to changes in the tension to which the strand is subjected.

8. A unitary elastic strand of a cross-sectional size suitable for incorporation in fabrics and having irregularly-disposed and irregularly-shaped differentially-colored areas or zones dispersed thereon and changeable in shape in response to changes in the tension to which the strand is subjected.

9. A unitary elastic strand of a cross-sectional size suitable for incorporation in fabrics and composed of a plurality of three-dimensional bodies of elastic material of differential coloration and shape, the said differentially-colored bodies being arranged in the strand in such manner as to change their shape in response to changes in the tension to which the strand is subjected.

FREDERICK P. JECUSCO.
